ABSTRACT OF THE DISCLOSURE

A railway appliance includes a derail and a blue flag signal forming a convenient, compact, self-contained unit. A hinged derail includes a base fixed to the roadbed and a derail block hinged to the base and having a derail shoe movable through an arcuate path between derailing and inactive positions. A blue flag signal including a staff and a sign is pivotally mounted on the base for movement independently of the derail block between signalling and inactive positions. Both the derail and the blue flag may be used alone, each being movable to its active position while the other remains in the inactive position. An interlocking feature is provided because the signal in its signalling position prevents movement of the derail from the derailing position. The signal is mounted to the base by a pin and slot connection, and the staff is releasably received in a latching recess in the signalling position.

The present invention relates to a safety appliance for railroads, and more particularly to a novel derail and blue flag signal unit.

Derails and blue flag signals are each safety devices widely used on railroads. A derail is a device placed on a track rail for derailing and thus effectively stopping a car or train which runs into the derail. For example, derails are used to protect a main line by preventing cars from entering the main line from a siding. A blue flag is a signal used on a railroad track, usually to protect humans or equipment on or about the track, and serves as a warning that the track must not be entered and that equipment on the track must not be coupled to or moved. A blue flag signal is customarily displayed above and between or beside the track rails, and normally comprises a flag or a sign having a blue color.

Situations where blue flags are used are often critical from a safety standpoint. For example, blue flag signals are used on track where cars are being loaded or unloaded, repaired, inspected and the like. It has been proposed to use both a blue flag and a derail in such situations so that the track is protected even if the blue flag is unheeded.

An important object of the present invention is to provide improvements in track safety equipment, and more particularly to provide a novel railway appliance including a derail having a blue flag permanently associated therewith so that their conjoint use is encouraged.

Another object is to provide a derail and blue flag in a self-contained unit and to provide such a unit in which either the blue flag or the derail may be used alone.

A further object is to provide an improved blue flag and derail unit wherein if the blue flag is in the signalling position, the derail cannot be moved off the rail.

Another object is to provide a derail including a blue flag signal which is releasably detained in its signalling position.

Briefly, the above and other objects of the invention are realized in one embodiment of the invention by the provision of an appliance including a derail and a blue flag signal forming a self-contained unit. A hinged derail includes a base adapted to be attached to the roadbed and a derail block hinged to the base having a derail shoe mov-

2

able between on rail and off rail positions. In accordance with a feature of the invention, a blue flag signal is also supported on the base for movement independently of the derail block between standby and signalling positions. The blue flag or the derail can be used alone since either can be moved to its operating position while the other remains in its inactive position. A safety interlock feature is provided in that when the blue flag is in its signalling position, the derail cannot be moved from its on rail to its off rail position. In addition, a novel arrangement is provided for releasably holding the blue flag in its signalling position.

The invention and its objects and advantages may be better understood from the following detailed description wherein reference is made to the accompanying drawings in which:

FIG. 1 is a perspective view of a derail and signal unit constructed in accordance with the invention and illustrated with the derail in the off rail position and with the signal in the standby position;

FIG. 2 is an elevational end view of the unit;

FIG. 3 is a view similar to FIG. 2 with the derail and signal in their alternate positions;

FIG. 4 is a top plan view of the unit as shown in FIG. 3;

FIG. 5 is an enlarged, fragmentary, sectional view taken 25 along the line 5—5 of FIG. 4; and

FIG. 6 is an enlarged, fragmentary, sectional view taken along the line 6—6 of FIG. 4.

Referring now to the drawings, there is illustrated a novel railway appliance in the form of a derail and signal unit constructed in accordance with the principles of the invention and designated as a whole by the reference numeral 10. The unit 10 is mounted in place on a track including crossties C and rails R, only one of which is illustrated in the drawings. The unit 10 serves to protect the track, and in accordance with the invention includes both a derail generally designated as 12 and a blue flag signal generally designated as 14 combined into a convenient, compact, self-contained unit.

The derail 12 for the most part may be of known construction and includes a derail shoe 16 movable between an off rail or closed position (FIGS. 1 and 2) in which the track is unobstructed and an on rail or open position (FIGS. 3 and 4) in which the shoe 16 guides a wheel moving along the rail off the rail onto the roadbed in order to halt a train or car.

In order to mount the derail 12 in a fixed position along the rail R, the derail includes a fixed supporting or base structure including a plate 18 attached to adjacent crossties C by spikes 20, as well as a plate 22 abutting the web of the rail R. A pair of vertically disposed members 24 support a hinge shaft 26 permitting movement of the derail shoe 16 between positions.

The derail shoe 16 forms part of a movable structure or derail block 28 including a pair of hinge plates 30 55 engaging the shaft 26. The shoe 16 is fastened to the outer most end of the hinge plates 30, so that when the block 28 is pivoted from its inactive, off rail position illustrated in FIGS. 1 and 2, the shoe 16 rests upon the upper surface of the ball of rail R in derailing position.

Although the invention is illustrated in connection with the unit 10 including the hinged derail 12, it should be understood that other types of derails could be used, as will be readily understood by those skilled in the art. For example, a sliding derail of the type wherein the derail block slides rather than pivots on the base could be used.

In accordance with the present invention, the signal 14 is associated with the derail 12 to form a compact, self-contained unit. The signal 14 includes a sign or panel 32, preferably blue in color, mounted on the end of a staff 34. The sign may carry a legend in contrasting color if

desired. The staff 34 is supported for pivotal movement on the base of the derail for movement of the signal 14 between a standby or inactive position illustrated in FIGS. 1 and 2, and a signalling or upstanding position illustrated in FIGS. 3 and 4, wherein the panel 32 is conspicuously disposed above and between the rails.

The combination of the derail 12 and blue flag signal 14 provides important advantages when the unit 10 is used to protect a track. When the signal 14 is in the signalling position and the derail 12 is in the derailing position as shown in FIGS. 3 and 4, workers or equipment on the track are safeguarded not only by the warning provided by the blue flag signal, but also by the fact that the derail prevents entry onto the track if the signal is not effective. Since both the signal and the derail are associated together in the unit 10, the blue flag signal cannot be lost or forgotten and the use of both elements simultaneously is encouraged.

One feature of the invention resides in the fact that either the derail or the blue flag signal can be used alone. In some situations, it may be desired to use the blue flag signal without the derail. When the derail is in its inactive closed or off rail position, the staff 34 and sign 32 can be pivoted to the signalling position without movement of or interference by the derail. Conversely, it may be desired to use the derail 12 without the blue flag signal 14. When the signal is in its standby position, the derail block 28 may be moved between positions without the necessity of moving the signal 14.

In many cases, it is desirable that the signal and the derail be used together. In accordance with one important feature of the invention, there is provided an interlocking action between the signal and the derail for assuring that the derail is not moved off of the rail while the signal remains up. Accordingly, when the signal 14 is in the upstanding or signalling position, the staff 34 intersects the arcuate path of movement through which the derail shoe 16 moves between the on rail and off rail positions. As a result, when the signal is in its upstanding signalling position, the derail cannot be moved between its positions. Due to this interlocking feature, a track worker cannot remove the derail from its derailing position without first lowering the blue flag signal.

In accordance with a further feature of the invention, there is provided a signal mounting assembly generally designated as 36 for pivotally or rotationally supporting the staff 34 and sign 32 on the derail 12. The mounting assembly 36 serves releasably to hold the signal in its upstanding or signalling position so that it cannot accidentally be knocked or blown down. In addition, the mounting assembly 36 suspends the signal in an unobtrusive position over the roadbed in its standby or inactive position.

More specifically, the staff 34 is interconnected to the plate 18 of the derail base by a pin and slot connection permitting the staff both to pivot and to reciprocate vertically with respect to the base. A pivot pin 38 (FIGS. 5 and 6) is supported by a bracket 40 attached to the staff 34 near its base. The staff is supported between a pair of pivot plates 42 supported on a base plate 44 attached to the plate 18. A pair of opposed slots 46 in the plates 42 receive the pin 38 so that the staff can pivot with respect to the derail base, and can also be moved axially in the direction of the slots.

When the signal 14 is moved to its upstanding signalling position as shown in full lines in FIGS. 5 and 6, the force of gravity moves the staff downwardly until its lower-most end rests upon plate 44. In this position, the staff is held in a latching recess defined between a pair of abutment members 48. The abutments 48 prevent the signal from being pivoted away from the signalling position until such time as the signal is lifted. Thus the signal cannot be accidentally lowered and cannot be blown down. In addition, the fact that the signal is releasably

latched in its signalling position increases the effectiveness of the interlocking action described above.

Lowering of the signal to its inactive position can only be accomplished by first raising the staff 34 clear of the abutments 48. The staff can then be pivoted downwardly to the standby position shown in broken lines in FIGS. 5 and 6. In this position the staff rests upon an abutment member 50, and the signal is suspended in an unobtrusive, generally horizontal position over the grade level of the roadbed and between the rails.

While the present invention has been described in connection with details of a certain embodiment thereof, many other modifications and embodiments may be devised by those skilled in the art. The invention is not limited to such details except as set forth in the following claims.

What is claimed and desired to be secured by Letters Patent of the United States is:

1. A railway appliance for use in track and comprising:

a base adapted to be fixed in position to the track roadbed adjacent a track rail;
a derailing structure including a derail support and a derail shoe carried by said support;
first pivotal mounting means pivotally interconnecting said derail support and said base for pivotal movement of said derailing structure relative to said base through an arc lying in a plane generally perpendicular to the track rail between a derailing position wherein said derail shoe rests upon the track rail and an inactive position wherein said derail shoe is laterally spaced from the track rail;
a signal staff including signal means located adjacent a first end of the staff; and
second pivotal mounting means pivotally interconnecting the second end of said staff and said base for pivotal movement of said signal means through an arc lying in a substantially vertical plane generally parallel to the track rail between standby and signalling positions;
said staff and signalling means in said standby position being substantially horizontally oriented and closely overlying said track roadbed and permitting free pivotal movement of said derail support and derail shoe; and
said staff and signal means in said signalling position being substantially vertically oriented and lying in the arc of pivotal movement of said derailing structure thereby to prevent movement of said derail shoe between positions only while said staff and signalling means are in said signalling position.

2. The appliance of claim 1 wherein said signal comprises a blue flag signal.

3. The appliance of claim 1, retaining means engageable with said staff in said signalling position for releasably holding said signal.

4. The appliance of claim 3, said retaining means comprising means connected between said signal and said base and permitting said signal to be moved downwardly in said signalling position, and means defining a recess for receiving said signal upon such downward movement for holding said signal until it is lifted from said recess.
